STAKING MACHINE

Johan F. Amelunxen, New Castle, Del., assignor
to F. F. Slocomb Corporation, Wilmington, Del.,
a corporation of Delaware

Application June 2, 1947, Serial No. 751,895

3 Claims. (Cl. 69—34)

1

This invention relates to leatherworking machines and more particularly to an improved mechanism for staking leathers and leather-like materials.

The art of staking leather has gradually progressed through the years from a manual operation involving heavy manual labor wherein the leather is manually drawn and flexed sharply over a narrow blade to a largely mechanical operation. The mechanical operation has heretofore commonly been performed on a machine in which the leather is sharply flexed over a blade superimposed between two pairs of coacting rotating members, the lower pair of members providing the necessary tension and spreading action to the leather and the upper pair of members acting to draw the leather upwardly over the blade and at the same time withdrawing the leather from the machine. U. S. Patent No. 2,238,413 to Larner Doughty, et al., is illustrative of the relatively recent advances made in the art.

It is an object of this invention to provide a readily adjustable staking machine having improved operating efficiency and flexibility.

It is a further object of this invention to provide a staking mechanism in which the gripping power of the drawing rolls may be effectively and conveniently controlled.

It is a further object of this invention to provide a staking machine having improved staking blade adjustment means.

Other objects of the invention will appear hereinafter, the novel features and combinations being set forth in the appended claims.

Generally described, this invention includes a frame member, an upper relatively fixed power roll, a spreader roll, a staking blade mounted therebetween, a relatively movable upper power roll and a tension roll mounted on an arm member, mechanism for rotating said power rolls and said spreader roll, and mechanism for actuating said arm member.

A preferred embodiment of the invention has been chosen for purposes of illustration and description and is shown in the accompanying drawings forming a part of the specification wherein like figures refer to like parts wherever they occur:

Fig. 1 is a front broken elevational view of the invention with all guards removed;

Fig. 2 is a fragmentary sectional view of the invention taken substantially along line 2—2 of Fig. 1;

Fig. 3 is an enlarged fragmentary sectional view of the staker blade adjustment means taken along line 3—3 of Fig. 2;

2

Fig. 4 is an enlarged fragmentary sectional view of the transfer and drive sleeve assembly taken along line 4—4 of Fig. 1.

With reference to the accompanying drawings 5 a frame 10 is shown having mounted thereon a relatively fixed power roll 11, preferably constructed with a rigid metal core shaft 12 covered with a resilient material 13, such as natural or synthetic rubber, for the entire length of the working face. The core shaft 12 is rotatably supported near the ends by bearing blocks 14 and rotated by driven gear 15 mounted upon an extension of the core shaft 12, said driven gear being in turn rotated by a drive gear (not shown) 10 mounted on a variable speed drive shaft 16 of a variable speed reduction unit 17. The variable speed reduction unit 17 is driven by an electric motor power unit 18, the rotative power being transmitted from the motor unit to the variable speed reduction unit by a plurality of V-belts 19 and 20.

An upper relatively movable power roll 21 and a relatively movable tension roll 22 are rotatably supported near their ends in parallel relationship by bearing pillow blocks 23 mounted upon pivotal arm members 24. The pillow blocks supporting the movable power roll 21 are adapted to be vertically adjustable by means of loosening mounting bolts 25 received in slotted recesses 26 and positioning by the proper setting of the hanger bolts 27. The composite construction of the movable power roll and tension roll is preferably similar to the construction of the fixed power roll described hereinabove.

The pivotal arm members 24 are mounted at 35 the lower extremity thereof upon a pivot shaft 28, pivotally supported by a pair of spaced bearings 29 rigidly attached to the base portion of the frame 10. A drive sleeve assembly 30, illustrated in detail in Fig. 4, is rotatably mounted upon an extremity of pivot shaft 28. Said drive sleeve assembly 30 consists of sleeve 31 rotatable upon the shaft 28, a sprocket 32 rigidly attached to said sleeve, and driven spur gear 33 rigidly attached to said sleeve opposite said sprocket. The drive 40 sleeve assembly is retained on the pivot shaft by a shaft collar 34 in juxtaposition to said sprocket and a safety collar 35 attached to said shaft in juxtaposition to said driven gear 33. Rotative power to effect rotation of the movable power roll 21 is transmitted from the sprocket 32 to a movable power roll sprocket 36 by a roller chain 37. Rotative power supplied by the motor unit 18 to the fixed power roll 11 is transmitted to the movable power roll 21 by a roller chain 38 connecting a fixed power roll sprocket 39 to a trans-

fer assembly 40 which in turn activates the driven spur gear 33 and sprocket 32 of the drive sleeve assembly. The transfer assembly 40 consists of a transfer sprocket 41 and an adjacent transfer spur gear 42 adapted to mesh with driven spur gear 33, said transfer sprocket and gear being rigidly attached to a bearing sleeve 43 adapted to rotate upon a bearing shaft 44 affixed to the frame 10. A spacer collar 45 and nut 46 threaded to said shaft 44 are adapted to retain the bearing sleeve 43 in place.

The proper tension is maintainable in the roller chains 37 and 38 by pivotally-mounted idler sprockets 47 adapted to be located so as to bear against the chain in an amount desired by pivotal adjustment of the idler sprocket mountings 48.

A spreader roll 49, of a construction familiar to those skilled in the art, having narrow blades 50 attached thereto to effect helices extending in reverse directions from the mid-section of the roll, is rotatably supported near the ends thereof by a pair of floating adjustable bearing blocks 51 contained by the frame 10. A lower constant speed drive shaft 52 with a drive sprocket 53 mounted thereon of the variable speed reduction unit 17 is adapted to rotate the spreader roll by means of a roller chain drive to the spreader roll sprocket 54.

A staker knife assembly 55 interposed between the fixed power roll 21 and the spreader roll 49 is made up of, with reference to Fig. 3, a blade member 56 of a length substantially equal to the length of the working face of the spreader roll 49, a blade support bar 57 to which the blade 56 is attached and support bar end pivot members 58 adapted to slidably receive each end of the support bar 57. A pivot pin 59 is rigidly secured to the frame 10 and adapted to permit the pivot members 58 to pivot freely thereabout. A threaded rod 60, lockable and rotatable in the end pivot members 58, is threadedly attached to the blade support bar 57 and thereby adapted to adjustably locate substantially horizontally each end of the support bar in the pivot members at the discretion of the operator. An adjustment bar 61 is rigidly attached to each pivot member at one end and connected to a threaded vertical adjustment rod 62 by a link bar 63 pinned to said vertical adjustment rod 62 and to said adjustment bar 61. An adjustment wheel 64, threadedly attached to said vertical adjustment rod 62, is rotatably mounted in an extended bracket 65 of said frame 10 and retained in place therein by a locking collar 66. Rotation of the adjustment wheels 64 will effect movement of the pivot members 58 about the pivot pins 59 and in turn effect a change in location of the staker blade member 56 with respect to the lower tension roll 22 at the discretion of the operator.

A table 67, preferably made of well-seasoned hardwood, forms a part of the frame 10 and is of great convenience in the productive operation of the invention.

The proper setting of the foot valve 68 by the operator to control the direction of flow of pressurized fluid to a pivotally-mounted cylinder assembly 69 connected through a system of connecting linkage to the pivotal arm members 24, effects the movement of said pivotal arm members in the desired direction. A piston rod 70 of the cylinder assembly 69, preferably provided with a cushioned stop at the end of each direction of stroke, is pivotally connected to a crank arm 71 which is rigidly attached to a control shaft 72. A connecting link 73 is pin-connected at one end thereof to a linkage crank 74 and at the other

end thereof to an arm adjustment bolt 75 adjustably attached to the arm members 24. The location of the adjustment bolt 75 may be readily adjusted to effect proper parallel relationship between the power rolls and thereby insure uniform pressure being applied throughout their length of contact. The control shaft 72 is rotatably supported at its ends by bearings 76 mounted on the frame 10.

10 The foot valve 68 is preferably of a type such as Lehigh Marton piston-type combination valve with foot release made by Lehigh Foundries, Lehigh-Marton Air Control Division, supplied with a pressurized fluid whose pressure may be conveniently controlled by the operator by means of a pressure control valve (not shown). It can thus be seen that the pressure of the upper movable power roll 21 against the fixed power roll 11 may be readily varied by the manipulation of the pressure control valve.

15 The pressure of the spreader roll 49 against the tension roll 22 may be conveniently adjusted through variance of the compression of the spring 77 by adjusting the threaded engagement of a compression adjustment bolt 78 in the floating bearing blocks 51.

20 The rotative speed of the power rolls is readily adjusted in a variable speed reduction unit 17 such as a positive, infinitely variable speed transmission (P. I. V.) made by the Link-Belt Company by rotating a speed adjustment wheel 79.

25 A guard plate 80 is preferably located below the spreader roll to deflect the ends of the hides away from the under side of the spreader roll. In practice, guards, not shown for the sake of clarity in the drawings, are constructed to enclose the moving parts such as gears, chains, sprockets and rolls as much as possible for maximum protection of the operator. A control switch 81 to start and stop the electric motor 18 is conveniently located on the frame 10 within easy reach of the operator.

30 In operation of the machine of this invention, the operator adjusts the rolls to the speed desired, manipulates the foot valve 68 to effect the movement of the upper movable power roll 21 away from contact with the fixed power roll 11, positions a hide to be softened in the space between the rolls, as illustrated in Fig. 2, and again manipulates the foot valve 68 to effect pressurized contact between the power rolls which draw the hide upwardly about the staking mechanism, thus staking approximately one-half thereof. The hide is then reversed in position, and the above operation is repeated to stake the opposite portion of the hide.

35 This machine has been found to greatly improve the product obtained in the staking operation and its versatility in adaptation to varying production conditions such as the staking of pig, goat, sheep, and calf skins, kips and sides has been outstanding in comparison with prior art constructions.

40 What I claim and desire to protect by Letters Patent is:

45 1. In a staking machine the combination of a frame member; an upper relatively fixed power roll; a spreader roll positioned substantially below said fixed power roll and mounted in adjustable floating bearing blocks; a staking blade supported between said fixed power roll and said spreader roll; substantially vertical adjustment means for said staking blade including a blade support bar and pivotal and supports for said bar; substantially horizontal adjustment means 50 for said staking blade; a relatively movable upper

power roll; a relatively movable tension roll; pivotally mounted arm members adapted to support said movable power and tension rolls; means for rotating said power rolls; means for rotating said spreader roll; and means for pivotally actuating said arm members.

2. In a staking machine, the combination of a frame member; an upper relatively fixed power roll; a spreader roll positioned substantially below said fixed power roll and mounted in adjustable floating bearing blocks; a staking blade supported between said fixed power roll and said spreader roll; substantially vertical adjustment means for said staking blade including a blade support bar, pivotal end supports for said bar, an adjustment bar rigidly attached to said pivotal end supports at one end and pinned to a threaded vertical adjustment rod at the other end, and an adjustment wheel threadedly attached to said vertical adjustment rod; substantially horizontal adjustment means for said staking blade; a relatively movable upper power roll; a relatively movable tension roll; pivotally mounted arm members adapted to support said movable power and tension rolls; means for rotating said power rolls; means for rotating said spreader roll; and means for pivotally actuating said arm members.

3. In staking machine, the combination of a frame member; an upper relatively fixed power roll; a spreader roll positioned substantially below said fixed power roll and mounted in adjust-

able floating bearing blocks; a staking blade supported between said fixed power roll and said spreader roll; substantially vertical adjustment means for said staking blade including a blade support bar, pivotal end supports for said bar, an adjustment bar rigidly attached to said pivotal end supports at one end and pinned to a threaded vertical adjustment rod at the other end, and an adjustment wheel threadedly attached to said vertical adjustment rod; substantially horizontal adjustment means for said staking blade including a threaded rod member lockably and rotatably attached to said blade support bar; a relatively movable upper power roll; a relatively movable tension roll; pivotally mounted arm members adapted to support said movable power and tension rolls; means for rotating said power rolls at a variable speed; means for rotating said spreader roll at a constant speed; and means for pivotally actuating said arm members.
